(57) **CLAIM**

The ornamental design for an adjustable princess dress, as shown and described.

DESCRIPTION

FIG. 1 is a perspective view of the adjustable princess dress, showing the new design;

FIG. 2 is a front elevational view of the adjustable princess dress thereof;

FIG. 3 is a rear elevational view of the adjustable princess dress thereof;

FIG. 4 is a left side elevational view of the adjustable princess dress thereof;

FIG. 5 is a top plan view of the adjustable princess dress thereof; and,

FIG. 6 is a bottom plan view of the adjustable princess dress thereof.

The right side elevational view of the adjustable princess dress is a mirror image of the left side view of the adjustable princess dress view shown in FIG. 4.

The broken lines illustrate environmental subject matter that form no part of the claimed design.

The broken lines illustrate portions of the article that form no part of the claimed design.

1 Claim, 6 Drawing Sheets
